UNITED STATES PATENT OFFICE.

JEWELL P. McLAURIN, OF DILLON, SOUTH CAROLINA.

BOTTLE STOPPER.

Application filed January 13, 1922. Serial No. 528,958.

To all whom it may concern:

Be it known that I, JEWELL P. McLAURIN, a citizen of the United States, and resident of Dillon, in the county of Dillon and State 5 of South Carolina, have invented certain new and useful Improvements in Bottle Stoppers, of which the following is a specification.

This invention relates to dust caps especially adapted for application to bottles.

An important object of this invention is to provide a dust cap for bottles which extends over the outlet end of the bottle for the purpose of protecting the bottle from dust, 15 whereby when the liquid is discharged from the bottle, it will not come in contact with the dust or dirt.

A further object of the invention is to provide a dust cap for bottles which may be used in conjunction with any kind of a bottle closure and which does not interfere with the free application or removal of the bottle closure.

Another object of the invention is to provide a dust cover for bottles which is of highly simplified construction, neat in appearance and cheap to manufacture.

Other objects and advantages of the invention will be apparent during the course 30 of the following description.

In the accompanying drawing forming a part of this application and in which like numerals are employed to designate like parts throughout the same,

Figure 1 is a side elevation of the improved dust cap applied.

Figure 2 is a vertical sectional view through the improved dust cap applied.

Figure 3 is a perspective of the dust cap.

Figure 4 is a side elevation of a modified form of the invention.

Figure 5 is also a side elevation of a further modification of the invention.

Figure 6 is a side elevation of a still further modification of the invention, the dust cap illustrated in this figure being also adapted to function as a closure protector.

The bottle is designated by the numeral 5 and may be of any desired type for receiving 50 such liquid as medicine extracts and the like. As illustrated in Figures 1 and 2 the upper portion of the bottle is provided with a neck 6 having an outlet and capable of being closed by a cork 8 of proper size. The outlet end of the bottle frequently becomes 55 coated with dust as a result of remaining on

a shelf for a long period and to overcome this objection I have provided a dust cap 10 of rubber or other suitable material. The dust cap 10 which is yieldable is normally of 60 the shape illustrated in Figure 3, that is to say of concavo-convex formation and is provided with a centrally arranged opening 11 adapted for the reception of the cork 8. The outer edge portion of the concavo-convex 65 body 11 is adapted to encircle the neck of the bottle and securely engage the same, whereby to prevent the dust and the like from lodging on the outlet end of the bottle. The yieldable body 10 not only firmly grips the 70 end of the bottle but also grips the cork so that dust will be prevented from passing between the cork and the adjacent edge of the yieldable body.

In applying the improved dust cap, the 75 cork is first inserted into the bottle and the cap is then slipped over the end of the cork and engaged with the end of the bottle. When applied the cap 10 remains in position and the cork 8 may be removed without the 80 necessity of removing the cap. Of course the opening 11 in the dust excluding body is in alignment with the opening in the neck of the bottle so that said cork may be readily inserted into the bottle. 85

In the form of the invention illustrated in Fig. 4 the cap is generally designated by the numeral 15 and is adapted to be applied to the neck of a bottle of any desired type. In this case the neck 16 is provided 90 with a cork 18 having a cork screw 19 connected thereto to form a means whereby the cork may be readily withdrawn. A cap when constructed in accordance with this form of the invention may be made of any 95 desired material and is provided with a downwardly extending side 22 adapted for overhanging the sides of the bottle neck, whereby to effectively prevent dust from lodging at the outlet end of the body. Also this form 100 of the invention overhangs the cork 18 so as to effectively prevent dust from lodging on the cork and also prevents dust from coming in contact with the liquid when dispensed. The shank of the cork screw is threaded 105 through a centrally arranged opening in the body 15 so that when the cork is removed the cap also will be removed.

In Figure 5 a cap 25 of any desired material is applied to the glass closure 26 of a bottle 27, the said bottle being provided 110 with a neck 28 having an opening to receive

the plug of the closure 26. The plug of the closure is provided with a shank 29 and with a handle 30 forming a means whereby the plug may be removed. In this form of the invention, the cap 25 is provided with a top extending over the plug of the closure and which extends over the upper end of the bottle so as to effectively prevent dust and dirt from lodging on the bottle. Also the downwardly extending side effectively prevents the dust from lodging on the side of the bottle neck. In this form of the invention also the cap 25 is removed with the closure.

15 In Figure 6 it will be observed that a cap 38 may be provided with a beaded edge 39 which draws the edge of the cap inwardly or constricts the opening in the cap so that when the same is applied to the neck 40 it will remain in position. In other words the bead 39 of the cap 38 is yieldable and draws the edge of the cap inwardly toward the neck of the bottle so that the cap will remain in position and also act as a retaining 25 means for the cork 44. As the cork 44 is engaged by the cap 38 the contents of the bottle will not be spilled in case the bottle is upset. Also the cap 38 extends completely over the cork so as to effectively exclude 30 dust.

With reference to the foregoing description it will be apparent that a bottle cap constructed in accordance with this invention may be economically manufactured and 35 placed upon the market and also the improved cap may be used in connection with a bottle closure of any type and when applied effectively prevents dust and the like

from lodging on the outlet end of the bottle and causing the liquid to come in contact 40 with the dust when dispensed.

Also it will be apparent that the inventive idea involved in this invention may be carried out in a variety of ways and therefore it is to be understood that the several forms 45 of the invention herewith shown and described are to be taken as preferred examples of the same and that such minor changes in the arrangement and construction of parts may be made as will remain 50 within the spirit of the invention and the scope of what is claimed.

In carrying out the invention the cap illustrated in Figures 1 to 3 may be of rubber so that the same will contract and engage 55 the neck of the bottle and the cork. Also in Figure 6 the cap may be made of rubber while the other forms of the invention, the cap may be made of any desired material. In the forms of the invention 60 employing rubber the cap may be readily removed and washed.

Having thus described the invention what is claimed is:—

An attachment for bottles comprising a 65 concavo-convex body of yieldable material adapted to be fitted over the outlet end of a bottle whereby to protect the same from dust, the central portion of said yieldable body being provided with an opening to snugly receive a cork, the wall of said opening being adapted to firmly grip the intermediate portion of the cork whereby to effectively exclude dust.

JEWELL P. McLAURIN.
